DESIGN FOR A SPOTTING BOARD UNIT

William M. Cissell, St. Mathews, near Louisville, Ky.

Application October 13, 1941, Serial No. 103,753

Term of patent 14 years

To all whom it may concern:

Be it known that I, William M. Cissell, a citizen of the United States, residing at St. Mathews, near Louisville, in the county of Jefferson and State of Kentucky, have invented a new, original, and ornamental Design for a Spotting Board Unit, of which the following is a specification, reference being had to the accompanying drawing, forming part thereof.

The opposite side from that shown in Fig. 1 is substantially the same except that the semi-circular name plate and the pedal control portions are omitted. The back of the article is substantially plain.

I claim:

The ornamental design for a spotting board unit, as shown and described.

WILLIAM M. CISSELL.
